VACUUM CLEANER

Erik Sigfrid Lynger, Stockholm, Sweden, assignor to Electrolux Corporation, Dover, Del., a corporation of Delaware

Application October 9, 1935, Serial No. 44,143
In Germany October 11, 1934

5 Claims. (Cl. 183—51)

My invention relates to vacuum cleaners and more particularly, to vacuum cleaners of the type wherein the dust separating member, such as a dust bag, is contained within a casing.

5 In cleaners of this type the dust separating member is removable through an opening for the purpose of removing accumulated dirt from the member. This opening must necessarily be closed, and the closure member is usually provided with an inlet opening to which may be secured a cleaning tool, either directly or by means of a flexible hose. In order to assure that all the dust is removed from the air drawn into the cleaner, it is necessary to cause all the air to pass through the dust separating member. In other words, a seal must be effected between the dust separating member and the casing to prevent the passage of air through the casing without passing through the dust separating member. 10 Likewise, it is necessary to prevent leakage between the casing and the closure member because such leakage would reduce the suction obtainable in the cleaning tool.

Among the objects of my invention is to provide improved structure for effecting a seal between the dust separating member and the casing, while at the same time preventing leakage between the casing and the closure member.

Another object of my invention is to provide improved and simplified means for securing the closure member to the casing.

Further objects and advantages of my invention will be apparent from the following description given in connection with the accompanying drawings which form a part of this specification and of which:

Fig. 1 is a view, partially in cross-section, of one embodiment of my invention;

Fig. 2 is a front view of a portion of the device shown in Fig. 1;

Fig. 3 is a view, partially in cross-section, of a second embodiment of my invention;

Fig. 4 is a view, partially in cross-section, of a third embodiment of my invention;

Fig. 5 is a cross-sectional view of a portion of the device shown in Fig. 4;

Fig. 6 is a cross-sectional view of a fourth embodiment of my invention;

Fig. 7 is a cross-sectional view of a fifth embodiment of my invention; and

Fig. 8 is a view, partially in cross-section, of a sixth embodiment of my invention.

Referring more particularly to Figs. 1 and 2, reference character 10 designates a casing, which may preferably be cylindrical. A ring 11 is suit-

ably secured to one end of casing 10 and is formed with an inwardly extending flange 12 provided with a sealing surface 13. Ring 11 is also provided with a second inwardly extending flange 14 which is interrupted by recesses 15. A dust separating member, such as dust bag 16 made of suitable cloth, or other material pervious with respect to air but impervious with respect to dust is formed with an open mouth secured to a dust bag ring 17. Ring 17 includes a cylindrical portion 18 to which the dust bag may be secured by means of glue and string or the like 19. The ring also includes a radial flange portion 20, the outer edge of which is enclosed within a grooved sealing ring 21 made of rubber or other suitable sealing material. The diameter of sealing ring 21 is greater than the internal diameter of flange 12 but less than the internal diameter of the interrupted flange 14. Consequently, the dust bag and the ring 17 may be inserted through ring 11 until the sealing ring 21 contacts the sealing surface 13 on flange 12.

Reference character 25 designates a closure member which is formed with an interrupted flange 26 which is adapted to cooperate with interrupted flange 14 in the manner of a bayonet joint. That is to say, the projections of flange 26 may be inserted through the recesses 15 of flange 14 and then turned through a slight angle so as to be retained underneath the projections of flange 14. Closure member 25 is provided with a central threaded opening 27 in which is received a threaded sleeve 28. Sleeve 28 is formed with an outer skirt 29, the outer surface of which may be formed with intersecting straight sides, 35 like a nut. The interior of sleeve 28 is formed with screw threads 30 adapted to receive a flexible hose leading to the cleaning tool. A bushing 31 is screw-threaded into the inner sleeve 28 and provides a recess between the inner end of the 40 sleeve and the bushing. An annular member 32 has its inner periphery turnably received within this recess. The outer edge of member 32 is adapted to contact sealing ring 21 on dust bag ring 17. Member 32 may, if desired, be made so 45 as to be resilient, although in this embodiment this is not necessary.

Also contained within casing 10 is a fan 35 driven by a conventional electric motor mounted within the casing. The casing is provided with 50 an air outlet opening 36. Runners 37 serve to support the casing in a substantially horizontal position on a horizontal surface.

The dust bag and closure member are placed in position in the casing in the following man- 55

ner: The closure member 25 being removed, the dust bag may be inserted through the opening in this end of the casing until the sealing ring 21 abuts the sealing surface 13 on flange 12. The projections on interrupted flange 26 of the closure member are then passed through the recesses 15 formed in interrupted flange 14 and the closure member is turned slightly so that the projections in the two flanges overlap, thus holding the closure member in place. Skirt 29 on sleeve 28 is then turned by hand in the proper direction to advance the sleeve inwardly. This causes member 32, carried by the sleeve, to contact sealing ring 21 and to press the sealing ring tightly against the flange 12. Due to the fact that sealing ring 21 is made of rubber, a large amount of friction exists between it and member 32. However, because of the turnable connection between this member and sleeve 28, it is not necessary to overcome this friction.

When fan 35 is rotated, it causes a current of air to be drawn in through sleeve 28 from the cleaning tool attached thereto. Inasmuch as ring 21 is pressed tightly against flange 12, all of this air must pass into the dust bag 16. Likewise, member 32 effects a seal between the dust bag ring and sleeve 28, whereby there is no tendency for air to leak into the casing at the joint between the casing and the closure member 25. Consequently, there is no necessity for making this joint airtight. The air drawn into the dust bag passes through the material thereof, while entrained dust is retained within the bag. The air, free of dust, is discharged by the fan through the outlet of the member 36.

It will be seen that the force exerted by member 32 against sealing ring 21 is equally distributed around the circumference of the ring, particularly if member 32 is made of resilient material. Consequently, the sealing surface 13 of flange 12 does not have to be accurately made inasmuch as any inaccuracies will be taken care of by this equalization of force. Moreover, it is not necessary to provide any means on the outside of the casing for securing the closure member in place, thus eliminating projections which might catch on and damage furniture or other objects. The force exerted by member 32 against ring 21 reacts through closure member 25 to ring 11, thus holding the overlapping projections on member 25 and flange 14 in frictional contact. This prevents accidental turning of the closure member, which might result in its release from the casing.

The embodiment shown in Fig. 3 is similar to that shown in Fig. 1, with the exception that member 32 is secured directly to closure member 25 instead of to a sleeve having threaded engagement with the closure member. In this case, member 32 is constructed so as to be resilient, inasmuch as no means is provided for tightening this member against the sealing ring. Also, in this embodiment, a somewhat different type of bayonet coupling for securing the closure member to the casing is employed.

The inner surface of ring 11 is provided with projections 40 which are adapted to be received within T-shaped slots 41 formed in closure member 25. The ends of the arms of the slots are formed with recesses 42 to prevent accidental turning of the closure member when in place.

In this embodiment, when the closure member is put in place, resilient member 32 bears against sealing ring 21 with an evenly distributed force resulting from the deformation of member 32,

thus preventing the passage of air between the sealing ring and the casing. As in the first embodiment, member 32 prevents the leakage of any air between the casing and the closure member.

In the embodiment shown in Figs. 4 and 5, the closure member 25 is securable to the ring 11 of casing 10 in the same manner as described in connection with Fig. 3, that is to say, projections 40 extend inwardly from ring 11 and are adapted to engage the T-shaped slot 41. The inner face of closure member 25 is provided with an annular groove 50 adjacent to the outer peripheral edge of the closure member and facing the sealing surface 13 on flange 12 when the closure member is in position. An annular ring 51 is slidably mounted within groove 50 and is T-shaped in cross-section. The branches 52 of the T contact the sides of the groove 50 and the fit therebetween is as close as possible without interfering with sliding movement. The stem 53 of the T is adapted to project out of the groove 50 and to contact the sealing ring 21. Resilient means, such as a spring 54, is provided between the bottom of the groove and the annular ring 51 and serves to urge the ring outwardly.

When the closure member is secured to the casing by means of bayonet connection 40, 41, the stem 53 of annular ring 51 contacts sealing ring 21 on the dust bag ring 17 and spring 54 causes annular ring 51 to press the sealing ring 21 against the sealing surface 13 on flange 12. Consequently, leakage of air between the sealing ring and the flange is prevented. Also, because of the close fit between annular ring 51 and the sides of the groove, air may not pass from between the casing and the closure member to within the dust bag.

In the embodiment shown in Fig. 6, the closure member 25 is securable to ring 11 in a manner similar to that described in connection with Figs. 1 and 2. Closure member 25 is provided with a central opening 70 within which is slidably received the cylindrical portion 71 of a sealing member designated generally by the reference character 72. Integral with cylindrical portion 71, or suitably secured thereto, is a threaded portion 73 which is adapted to receive an air hose or other suction cleaning implement. Sealing member 72 also includes an annular portion 74, the outer edge of which is adapted to engage the sealing ring 21 of the dust bag 16. A coil spring 75 is arranged between closure member 25 and sealing member 72 and tends to force the latter inwardly.

When closure member 25 is secured in place, sealing member 72 contacts sealing ring 21 and presses the latter against the sealing surface 13 formed on flange 12. This force results from the stressing of spring 75. In this embodiment, due to the pressure of spring 75, it is not necessary that sealing member 72 be resilient, although it may be if desired.

The embodiment shown in Fig. 7 differs from that shown in Fig. 6 chiefly in that spring 75 is omitted. Consequently, it is necessary to construct sealing member 72 in a resilient manner so that it may be deformed slightly when the cover member is in place in order to provide the force necessary to press ring 21 into sealing contact with surface 13. In the devices shown in both Figs. 6 and 7, cylindrical portion 71 is rotatably mounted in cover member 25 so that the cover member may be turned slightly, for the purpose of engaging the bayonet joint, without turning the sealing member 72, thus making it

unnecessary to overcome the friction between the sealing member and the rubber sealing ring 21.

In the embodiment shown in Fig. 8, an annular ring 80 of flexible rubber or the like is secured to a cylindrical flange 81 formed on closure member 25. In order to allow turning between the ring 80 and the closure member, thus preventing torsional stress in the ring, an annular liner 82 of metallic material may be interposed between ring 10 80 and flange 81. The friction between ring 80 and liner 82 is high, due to the nature of the material of ring 80, but the friction between liner 82 and flange 81 is low, thus permitting easy turning. In order to obtain a tight seal between 15 rings 80 and 21, the former is preferably dished, as shown in Fig. 8, in order that the pressure difference existing inside and outside of ring 80 may aid in forcing ring 81 in contact with ring 21.

When closure member 25 is secured in place, 20 the deformation of ring 80 creates a force which presses ring 21 against sealing surface 13 on flange 12, thus preventing the leakage of air therebetween. As above pointed out, when the fan is started, the pressure difference thereby 25 created increases the force exerted by ring 80 against ring 21, thereby increasing the sealing effect. Ring 80 likewise prevents leakage of air between the closure member and the casing.

While I have shown and described several 30 embodiments of my invention, it is to be understood that this has been done for the purpose of illustration, and that my invention is not limited thereby, but its scope is to be determined by the appended claims viewed in the light of the prior 35 art.

What I claim is:

1. In a vacuum cleaner, a casing formed with an opening, means forming a seat adjacent to said opening, a ring, a dust separating member 40 secured to said ring, an openable cover member securable to said casing for substantially closing said opening, said dust separating member being insertable through said opening when said cover member is open, an air impervious sealing member 45 provided with an air inlet and carried by said cover member and adapted to engage said ring and clamp the same in airtight relation between said sealing member and said seat when said cover is closed, said sealing member preventing flow of air from between said cover member 50 and said casing to said dust separating member.

2. In a vacuum cleaner, a casing formed with an opening and an internal flange adjacent to said opening, a ring, a dust separating member 55 secured to said ring, a cover member formed with an aperture, means for removably securing said cover member to said casing for closing said

opening, and an annular air impervious sealing member carried by said cover circumferentially of said aperture and adapted to resiliently engage said sealing ring and clamp the same in air-tight relation between said sealing member and said flange, said sealing member preventing flow of air from between said cover member and said casing to said dust separating member. 5

3. In a vacuum cleaner, a casing formed with an opening and an internal flange adjacent to 10 said opening, a sealing ring, a dust separating member secured to said ring, a cover member formed with a threaded aperture, means for removably securing said cover member to said casing for closing said opening, a threaded sleeve 15 turnable within said aperture and adapted to engage a suction cleaning device, an annular air impervious sealing member carried by said sleeve in air-tight relation thereto and adapted by turning of said sleeve to engage said sealing ring and 20 clamp the same in air-tight relation between said sealing member and said flange, said sealing member preventing flow of air from between said cover member and said casing to said dust separating member. 25

4. In a vacuum cleaner, a casing formed with an opening and an internal flange adjacent to said opening, a sealing ring, a dust separating member secured to said ring, a cover member formed with an aperture, means for removably 30 securing said cover member to said casing for closing said opening, an annular air impervious sealing member carried by said cover circumferentially of said aperture, and means for resiliently urging said sealing member against said 35 sealing ring to clamp the latter in air-tight relation against said flange, said sealing member preventing flow of air from between said cover member and said casing to said dust separating member. 40

5. In a vacuum cleaner, a casing formed with an opening and an internal flange adjacent to said opening, a sealing ring, a dust separating member secured to said ring, a cover member formed with an aperture, means for removably 45 securing said cover member to said casing for closing said opening, and an annular air-impervious sealing member constructed of resilient material carried by said cover circumferentially of said aperture and adapted to engage said sealing ring and clamp the same in air-tight relation between said sealing member and said flange, said sealing member preventing flow of air from between said cover member and said casing to said dust separating member. 50 55

ERIK SIGFRID LYNGER.
